UNITED STATES PATENT OFFICE.

FRANK Z. HANSOM, OF ELMHURST, ILLINOIS.

RETAINER FOR DENTAL PLATES.

1,201,177.

Specification of Letters Patent. Patented Oct. 10, 1916.

Application filed June 10, 1916. Serial No. 102,888.

To all whom it may concern:

Be it known that I, FRANK Z. HANSOM, a citizen of the United States, residing at Elmhurst, in the county of DuPage and State of Illinois, have invented certain new and useful Improvements in Retainers for Dental Plates, of which the following is a specification.

This invention relates particularly to lower plates, and means for holding or assisting in holding them in position.

The difficulty of keeping a lower plate in position is commonly understood, and this difficulty increases as the gums recede, making a shallow gum formation.

The objects of the present invention are to provide a lower plate which may be held more securely in position than the ordinary plate; to provide a dental plate with means adapted to co-act with the tongue for holding the plate in position; to provide integral or attachable projections or members in connection with lower dental plates for holding the same in position; and in general, to provide such advantages and improvements as will appear more fully hereinafter.

In the accompanying drawing illustrating this invention: Figure 1 is a plan view 30 of a dental plate, showing one form of my improvement; Fig. 2 is a detail of one of the attachable lugs or projections; Fig. 3 is an enlarged cross sectional view of one side of a plate, showing the retainer attached thereto; and Fig. 4 is a similar sectional view showing the retainer formed integrally with the plate.

In order to assist in holding a lower dental plate in position, this invention 40 contemplates the provision of a projection or projections which co-act with some portion of the mouth other than the gums, and preferably the tongue, for holding the plate in position. As illustrated in Figs. 1 and 3, the plate 5 is of any ordinary construction, having the usual groove 6 for engagement 45 with the gum, this groove being shown shallow, as is necessary when there is a shallow gum formation. Two lugs or projections 7 are secured to the opposed inner

faces or walls of the plate, being held in any suitable manner, as by means of strips 8, which are fastened to the projections and are then fastened by means of screws or pins 9 to the plate. The projections or 55 ledges 7 are preferably arranged so that their lower faces 10 will not come in contact with the floor of the mouth, while their upper faces 11 are adapted to be engaged by the lower surface of the sides of the 60 tongue. These ledges or projections may be made of any suitable material, such for instance as flexible rubber, hard rubber or the like, which is commonly used for forming the plates, and their outer faces 12 65 should fit closely against the inner wall of the plate, and perhaps be cemented thereto so as not to leave any cracks or recesses which would cause insanitary conditions.

In the modification shown in Fig. 4, the 70 plate 13 is provided with an integrally formed ledge or projection 14 similar in all respects to the ledges or projections 7 above described. These ledges or projections may be extended as far around the 75 inner surface of the plate as may be desirable or convenient to the wearer.

A plate constructed in accordance with my invention is used in the ordinary manner, with the exception that the tongue 80 tends to press down on the ledges or projections, and thereby soon acquires an additional function; namely, that of holding the plate in position. I have found in actual practice that plates made in accordance with this invention are much more readily retained in position, and the tongue of the wearer soon becomes accustomed to holding the plates in the manner described.

Having thus described my invention, 90 which, however, I do not wish to limit to the exact form or arrangement herein shown and described, except as specified in the following claims, what I claim and desire to secure by Letters Patent is:

1. A dental plate having two inwardly projecting rigid ledges arranged on the opposed inner surfaces of the plate, the lower faces of these ledges being arranged so as not to come in contact with the floor of the 95 100

mouth, while the upper faces are arranged to be engaged by the lower surface of the sides of the tongue.

2. A rigid lug or projection adapted to be secured to the inner side of a lower dental plate for engagement with the lower surface of the tongue, and means for securing said lug or projection to the plate.

3. A lower dental plate having rigid integrally formed inwardly extending ledges 10 at the sides only thereof for engagement with the lower surface of the tongue of the wearer, whereby the tongue will tend to hold the plate in position.

FRANK Z. HANSCOM.
